UNITED STATES PATENT OFFICE.

ALEXANDER M. BENNETT, OF BELLAIRE, MICHIGAN.

IRONING-BOARD AND SUPPORT.

SPECIFICATION forming part of Letters Patent No. 427,542, dated May 13, 1890.

Application filed May 16, 1889. Serial No. 310,933. (No model.)

To all whom it may concern:

Be it known that I, ALEXANDER M. BENNETT, a citizen of the United States, residing at Bellaire, in the county of Antrim and State 5 of Michigan, have invented a new and useful Ironing-Board and Support, of which the following is a specification.

This invention has relation to an ironing-board and support for the same.

10 Among the objects in view are to provide an ironing-board so constructed as to be adapted for connection with a support and adapted for the ironing of ordinary pieces of clothing and also the bosoms of shirts and 15 the sleeves of other articles of wearing-apparel.

A further object of the invention is to provide a light yet stable support for the board so constructed as to readily fold when not in 20 use and arranged to support and dry clothing and also to encircle a stove, whereby the clothes are brought in close proximity to the stove, regardless of the portion of the frame upon which they are hung.

25 Referring to the drawings, Figure 1 represents a perspective of my improved clothes-rack, the ironing-board being mounted thereon. Fig. 2 is a front elevation of the rack open, the ironing-board being removed. Fig. 3 is a 30 bottom perspective of the ironing-board detached. Fig. 4 is a detail section to show how the ironing-board is held in position.

Like numerals of reference indicate like parts in all the figures of the drawings.

35 1 represents opposite vertical standards, the upper halves of which are preferably cylindrical, and which are connected by a suitable tie-bar 2 at their middle and diagonal brace-rods 3 below the same. Above the tie 2 are 40 mounted one or it may be a series of adjustable clothes-receiving bars 4, provided with openings 5 at their ends for the passage therethrough of the circular uprights 1. A tie-bar 6 connects the upper end of the uprights or 45 posts 1, and also serves as an additional apparel-supporting bar.

Upon each of the supports 1 are pivoted short bars 7, having perforations 8 at their extremities for the passage of the bars 1 and 50 at their outer ends for the passage of studs 8* upon the ends of short posts 9. The bottom ends of the posts 1 and 9 are mounted

pivotal in connecting base-bars 10, and diagonal braces 11 cross each other, connecting the base-bars 10 with the bars 7. A removable longitudinal bar 12 connects the two posts 9, and a short diagonal brace 13 extends from the upper end of one bar 9 to near the lower end of the opposite companion bar. A long diagonal brace 14 extends from the upper end of the companion bar 9, is connected by nails or otherwise to the opposite bar 9, and passes by the same and terminates in a projection 15, the end of which is in a plane with the bottom of the frame-work. From 65 this description it will be seen that each end of the main frame comprising the bars 1, the diagonal braces 3, and the tie-bar 2 is provided with a pivotally-connected side frame composed of the bar 7 and base-bar 10, their 70 braces, and the vertical post 9, and that one of the side frames is provided with a folding longitudinal intermediate frame adapted to connect the free ends of the side frames. It will also be apparent that these side frames 75 may be folded against the main frame and the entire frame-work set to one side and out of the way. The frame as thus constructed is especially designed to open and encircle a stove and to receive and support numerous 80 articles of wearing-apparel and dry the same as other articles are being subjected to the operation of ironing.

16 represents the ironing-board, one end of which is formed with a projecting shirt-receiving bosom-board 17, which projects beyond the frame-work of the support and to that side thereof at which is located the extended diagonal brace 14. Upon the under surface of the board 16 is mounted a transverse block 18, having a diagonal recess or gain 19 formed therein, and seated within the same and secured to the under surface of the board is a diagonally-disposed arm-receiving tapered ironing-board 20, upon which are 95 adapted to be ironed the sleeves of garments, the board being reversed when it is desired to bring this sleeve-board into position. An arm 21 projects in a direction opposite from and is secured to the board 20, and is parallel 100 with the board 16 and spaced therefrom by a space-block 22, the office of this arm 21 being to form a space, in conjunction with the board 16, for the insertion of the bar 7 of one

- of the side frames. By this construction it will be apparent that pressure may be applied to the bosom-board 17, and the ironing-board will be prevented from tilting, it being held 5 in place by the arm 21. By reason of the elongated or extended diagonal brace 14 the frame-work as a whole will also be prevented from tipping when pressure is applied to the ironing-board 17.
- 10 Having described my invention, what I claim is—
1. The combination, with the central main frame, of oppositely-pivoted side frames provided with cross-bars, said side frames being 15 adapted to be swung to a right angle to the main frame and rest upon the floor, forming a base, an ironing-board mounted on the same and provided with an inclined sleeve-board, and an end arm projecting from and 20 supported by the sleeve-board and adapted to take under one of the cross-bars, substantially as specified.
  2. The combination, with the main frame composed of uprights, longitudinal clothes-receiving bars, a tie-bar, and diagonal braces connecting the uprights, of opposite side frames pivotally connected to the uprights and consisting of opposite upper and lower bars diagonally braced and connected at their 25 ends, and an intermediate frame hinged to and connecting the outer ends of the side frames, and a laterally-extending diagonal elongated bar mounted in the frame and projecting at one side and terminating in a plane 30 with the lower edge of the main frame, and a removable ironing-board mounted on the side 35

frames and provided with a bosom-board projecting over and beyond the side frame, beyond which the elongated bar projects, substantially as specified.

3. A reversible ironing-board, the under surface of which is provided with an inclined sleeve-receiving board, in combination with a space-block for the ironing-board, said inclined board taking under the same, and with 45 the arm 21 projecting from the rear end of the sleeve-board and parallel with the ironing-board, substantially as specified.

4. The combination, with the uprights 1, having the opposite pivoted bars 7 and 10, 50 connected to the uprights, and braced by diagonal bars 11, and provided with uprights 9, pivoted therein, and connected by a central connecting-frame consisting of a longitudinal connecting-bar 12, and oppositely-arranged 55 inclined braces 13 and 14, the latter extended, as at 15, of the board 16, having the bosom-board 17 formed at one end and above the projecting brace 15 and provided upon its under surface with the block 18, recesses, as at 60 19, and having the board 20 seated therein, and the arm 21, having the space-block 22, projecting from the board 20 and adapted to take under one of the bars 7, substantially as specified.

In testimony that I claim the foregoing as my own I have hereto affixed my signature in presence of two witnesses.

ALEXANDER M. BENNETT.
